UNITED STATES PATENT OFFICE.

STEPHEN HIPKINS, OF MARTINS FERRY, OHIO.

DESIGN FOR A HEADLIGHT-LENS.

54,504.

Specification for Design.

Patented Feb. 17, 1920.

Application filed March 17, 1919. Serial No. 283,272. Term of patent 3½ years.

To all whom it may concern:

Be it known that I, STEPHEN HIPKINS, a citizen of the United States, residing at Martins Ferry, in the county of Belmont and State of Ohio, have invented a new, original, and ornamental Design for Headlight-Lenses, of which the following is a specification, reference being had to the accompanying drawings, in which—

Figure 1 is a front elevation of a headlight lens, illustrating my new design, and—

Fig. 2 is a section of the same on the line 2—2, Fig. 1.

I claim:

The ornamental design for a headlight lens, substantially as shown.

STEPHEN HIPKINS.
